CLAIM

The ornamental design for a surgical instrument assembly, as shown and described.

DESCRIPTION

FIG. 1 is a perspective view of a surgical instrument assembly.

FIG. 2 is a right elevational view of the surgical instrument assembly of FIG. 1.

FIG. 3 is a left elevational view of the surgical instrument assembly of FIG. 1.

FIG. 4 is a front elevational view of the surgical instrument assembly of FIG. 1.

FIG. 5 is a rear elevational view of the surgical instrument assembly of FIG. 1.

FIG. 6 is a top plan view of the surgical instrument assembly of FIG. 1; and,

FIG. 7 is a bottom plan view of the surgical instrument assembly of FIG. 1.

The broken line in the drawings is included for the purpose of illustration portions of the surgical instrument assembly and forms no part of the claimed design.
